UNITED STATES PATENT OFFICE.

SAMUEL J. DELANEY, OF OAKLAND, CALIFORNIA.

COMBINATION CONVECTION AND RADIANT HEATER.

Application filed March 23, 1925. Serial No. 17,511.

This invention relates to heating appliances for heating rooms, dwellings and the like, and especially to heaters which burn gas as a fuel.

Heaters of this character are usually divided into two classes, to-wit, radiant heaters and convection heaters. Both types when vented are usually only about fifty per cent. efficient, when the actual heat units liberated in a room are considered, and when unvented they are a source of danger as the products of combustion are liberated directly in the room being heated.

The object of the present invention is to generally improve and simplify the construction and operation of heaters of the character described; to generally improve the heating efficiency by providing a combination convection and radiant heater operated from a common burner and which will insure the circulation of the air, so that two or more rooms may be heated with one heater; and further, to provide a structure which is vented in such a manner that none of the products of combustion will enter the room or rooms being heated.

One form which my invention may assume is exemplified in the following description and illustrated in the accompanying drawings, in which—

Fig. 1 is a perspective front view of the gas heater.

Fig. 2 is a perspective view of the innermost casing, the other casings being indicated by dotted lines.

Fig. 3 is a vertical section taken on line 3—3 of Fig. 6.

Fig. 4 is a vertical section taken on line 4—4 of Fig. 6.

Fig. 5 is a vertical section taken on line 5—5 of Fig. 6.

Fig. 6 is a cross section on line 6—6 of Fig. 4.

Referring to the drawings in detail, and particularly to Fig. 1, A indicates in general the heater forming the subject matter of the present invention. It consists of a base section 2 on which is mounted a rectangular-shaped casing. This casing consists of a front plate 3, side plates 4 and a rear plate 5. The front plate 3 has an opening formed therein as indicated at 6 and a series of radiant elements, hereinafter to be described, are supported by the base 2 and are disposed directly in back of the same. The casing is otherwise provided with a top or cover sec-

tion 7 which has a series of openings 8 formed therein for the escape of heated air.

Mounted inferiorly of the main casing is a second casing consisting of front, rear and side plates generally indicated at 9, 10 and 11 respectively. These plates are supported by the base and they are interspaced with relation to the exterior casing to form an air passage generally indicated at 12.

The casing consisting of the plates 9, 10 and 11 will hereinafter be referred to as the intermediate casing as a third casing is employed which also consists of front, rear and side plates as indicated at 13, 14 and 15. This last-named inner casing is spaced with relation to the intermediate casing and a series of passages for the escape of the products of combustion are formed thereby.

By referring to Figs. 3, 4 and 5 it will be noted that the plates 9, 10 and 11 forming the intermediate casing extend from the base to the point indicated at 16, and similarly that the plates 13, 14 and 15 of the innermost casing also extend to the same point.

This is important as it forms a main central passage 17 and intermediate passages 18, 19—19 and 20. The front plate 13 of the innermost casing connects the end walls 11 of the intermediate casing up to the point indicated at 21, as indicated by the full lines at 22. (See Fig. 6.) The plate is then cut away up to the top portion 16 and thus forms a pair of side openings which connect with the side passages 19.

The side plates 15 of the innermost casing extend from the point 23 to the rear plate 10 of the intermediate casing, as indicated by full lines at 24, and from the point 16 to the point indicated at 25. They are here cut away, as shown, and thus form a connection between the end passages 19 and a rear passage 20. This passage is provided with a vent pipe 26, which may be connected with a stack or flue of a chimney.

The radiant elements previously referred to are disposed rearwardly of the opening 6, and while they may be constructed in any manner desired, it is preferable to employ a rear glow plate 27 and a grill plate 27. These plates are separated to form a passage 29 and a gas burner of suitable construction is disposed directly below this passage as indicated at 30. The passages 18 and 29 align and the products of combustion will therefore escape upwardly through the passage 18. They will then enter the side

passages 19, where they will pass downwardly in the direction of the arrows, and they will finally escape into the rear passage 20, where they will pass upwardly and discharge through the vent 26. The gases are in this manner directed upwardly and downwardly around the passages formed between the innermost and the intermediate casings. These will, of course, become heated by the 10 escaping hot gases or products of combustion and an upward air flow will be induced through the passage 12 and an upward current of air will also be induced through the central or innermost passage 17, this being 15 possible as the base 2 is open to permit the entrance of air, and the cover 7 is provided with openings 8 to permit the air flow thus induced to freely escape into a room. This air is heated by convection only and is in 20 no manner contaminated with the products of combustion and may therefore be continuously circulated without danger of contaminating the air of the room.

The heat thus imparted is, of course, taken 25 from the products of combustion which are escaping and these are thus cooled and have lost most of their heat units before they escape through the vent 26. The heat is, of course, primarily obtained by the flame 30 of the gas burner indicated at 30, but this heat is also liberated by radiation, as the glower plate and the grill are constantly throwing off radiant heat.

From the foregoing it can be seen that 35 the combined advantages of a radiant and convection type of heater are obtained. Instantaneous heat and a cheerful appearance of the flame are obtained the moment the burner is lighted, and positive circulation of 40 air in the room or of several rooms is insured. The heating surfaces subjected to the action of the hot gases or products of combustion are, of course, scientifically designed to reduce the temperature of the escaping 45 products of combustion as much as possible and high efficiency of the convection part of the heater is thus obtained.

All products of combustion are thoroughly 50 vented and danger of polluting or otherwise affecting the air of the room or rooms being heated is prevented as sufficient temperature is maintained in the escaping gases to insure a proper draft.

By referring to Figs. 3, 4 and 5 it will be 55 noted that the upper ends of the passages 18, 19-19 and 20 are provided with angularly disposed cover sections such as shown at 40. This is important as it prevents the collection of dust or other articles which might 60 fall through the openings 8 in the upper cover plate 7. The lower part of the front portion of the passage 12 is similarly provided with an inclined bottom section as indicated at 41. This serves two functions, 65 first, that of preventing the collection of ma-

terial, and secondly, that of providing an inclined hood for the radiant elements previously described, thereby further preventing escape of products of combustion.

The exterior casing, consisting of the 70 plates 3, 4 and 5, does not only serve the function of forming an exterior passage such as indicated at 12, but also prevents excess heating of the exterior surface, thus eliminating the danger of burning a small 75 child if it should touch or fall against the same. The low temperature maintained is of further importance as it permits the exterior casing to be lacquered, enamelled or finished in any manner desired.

While certain features of the present invention are more or less specifically illustrated, I wish it understood that various changes in form and proportion may be resorted to within the scope of the appended 85 claims. I similarly wish it understood that the materials and finish of the several parts employed may be such as the experience and judgment of the manufacturer may dictate or various uses may demand.

Having thus described my invention, what I claim and desire to secure by Letters Patent is—

1. A heater of the character described comprising a main exterior casing vertically 90 disposed and elongated, and rectangular in shape in cross section, a base member forming a support therefor, a perforated plate forming a cover, an intermediate casing supported by the base and interspaced with 100 relation to the exterior casing to form an air heating passage in communication with air inlet openings formed in the base and with the perforated cover, an inner casing disposed within the intermediate casing and interspaced therefrom to form a front passage, a rear passage and a pair of side passages, a gas burner, means for directing the products of combustion liberated by the burner upwardly into the front passage, 105 baffle members directing the products of combustion downwardly through the side passages and then upwardly through the rear passage, and a vent pipe connected with the upper part of the rear passage.

2. A combination convection and radiant heater comprising an exterior, an intermediate and an inner casing, said casings being substantially rectangular in cross-section and interspaced with relation to each other to 110 form an exterior heating passage, a central air heating passage and a series of intermediate passages for the reception of products of combustion, a base member supporting said casings and having openings formed therein in communication with the inner and the exterior air heating passages, a cover member supported by the exterior casing, said cover member being perforated to permit heated air to escape therethrough, said 115

exterior casing having a front opening formed therein, said intermediate casing also having an opening formed therein in alignment with the front opening, a gas burner disposed below the opening in the intermediate casing, radiant elements disposed in the opening in the intermediate casing and above the burner and exposed to the atmosphere through the front opening in the exterior casing, means for directing the products of combustion from the burner and the radiant elements into the intermediate passages, vapor plates in said passages deflecting the products of combustion upwardly and downwardly during their flow through 15 said passages, and a vent pipe connected with one of the intermediate passages to carry away the products of combustion.

SAMUEL J. DELANEY.
